UNITED STATES PATENT OFFICE.

DAVID A. GRANT, OF PHILADELPHIA, PENNSYLVANIA.

RANGE-DEFACING MEANS FOR TIME-FUSES.

1,238,661.

Specification of Letters Patent. Patented Aug. 28, 1917.

Application filed April 13, 1916. Serial No. 90,823.

To all whom it may concern:

Be it known that I, DAVID A. GRANT, a citizen of the United States, residing at Philadelphia, in the county of Philadelphia and State of Pennsylvania, have invented certain new and useful Improvements in Range-Defacing Means for Time-Fuses, of which the following is a specification.

My invention relates to time fuses used for igniting shells, projectiles, shrapnel and the like, and particularly to time fuses employing a rotatable member which is set in a certain position in relation to a fixed member to determine the time of the explosion of the shell.

Time fuses are provided with a graduated scale, usually located upon the fixed member or body portion, said scale indicating seconds of time, and the opposite, or rotatable member, is provided with an arrow or indicating point. The rotatable member may be turned to bring the arrow adjacent to any desired point upon the graduated scale, and thus set the fuse to explode at a specified time.

The object of my invention is to construct a time fuse in such a manner that the indicating point or the graduated scale may be removed or defaced after the fuse is set and before the shell is fired from the gun, to destroy all evidence of the time allowed when setting the fuse, for the travel of the shell from the gun to the place where the shell hits. The purpose of this is to prevent the enemy from obtaining the range at which the fuse is set by examining the indicating marks upon the fuse of an unexploded shell, and thus obtaining the firing range.

In the accompanying drawings Figure 1, 40 is a side elevation of a fuse showing my improved detachable band or sleeve secured to the body portion of the fuse; and having the graduated scale formed upon said band; Fig. 2 is a similar view showing the detachable band secured to the rotatable timing ring of the fuse, and having a single indicating mark upon the band, the graduated scale being formed upon the body portion of the fuse in the usual manner; Fig. 3 is a perspective view of the band or sleeve, detached. Fig. 4, is a side elevation of a fuse, drawn on a smaller scale, showing two detachable bands, one thereof secured upon the rotatable ring and the other secured upon the body portion of the fuse; and Fig. 5 illustrates a different method of carrying out my invention.

tion, by providing a removable indicating pin in one of several apertures formed in the fuse.

Referring to the drawings in which like references refer to like parts, 1 represents the detachable metal band or sleeve upon which are shown graduations indicating seconds of time, and also having a second scale indicating yards. The band 1 is adapted to be secured to a time fuse, as shown in Fig. 1.

The fuse shown in the drawing consists of a body portion 2, provided with a threaded shank 3, for securing the fuse in a shell or projectile. The body portion 2 is provided with the nose portion 4 which is rigidly secured in the body portion 2. Between the body portion 2 and the nose portion 4, of the fuse is formed an annular groove in which is rotatably mounted the timing ring 5 and having an arrow or mark 6 formed thereon.

The timing ring 5 is rotated so as to bring the arrow 6 to any desired point upon the graduated scale upon the band 1. This will govern the time required for the fuse to explode after it has been fired from the gun. In Fig. 2 my improved graduated band 1 is shown secured to the rotatable timing ring 5 and the arrow 7 is shown located upon the band and used upon a fuse having the graduated scale located upon the body portion in the usual manner.

The metal band 1 may be made circular but I prefer to make it in a flat strip and secure the ends thereof together, so that the band may be more readily removed from the fuse.

In the drawings I have shown the metal band 1, with a fastening device consisting of a tongue 9 formed upon one end of the band and the opposite end of the band is shown with an aperture 10 formed therein to receive the tongue 9, which latter is bent over upon itself after it has been passed through the said aperture. This will hold the ends of the band together and the band may be readily removed by tearing off the tongue or straightening out the tongue so that it may be withdrawn through the aperture 10.

A small extension forming a handle 12 may be formed upon one of the ends of the scale to facilitate removing the band from the fuse. To prevent the band 1 from turning upon the fuse, lugs 13 may be formed upon the inner surface of the band, and said lugs 13 may enter small recesses

formed in the fuse to prevent the band from turning upon the fuse.

Any suitable form of fastening device may be employed for securing the band upon the fuse without departing from my invention. The removable band may be attached to either the fixed part of the fuse or to the rotatable part and it may be so arranged that the detachable sleeve will carry a single

mark or arrow in place of the graduations.

It may be found advantageous to use two detachable bands 1 and 1^a upon the same fuse, as shown in Fig. 4. One of the bands, as shown in Fig. 4, may be attached to the body portion 2, and the other one of said bands may be attached to the timing ring, as shown in Fig. 4. Said bands have the necessary indicating marks formed thereon, and the bands are adapted to be operated in conjunction with each other, thus eliminating all indicating marks from the fuse when the detachable bands are removed.

Another method of carrying out my invention is shown in Fig. 5, which represents the ordinary fuse, with the graduated scale formed upon the body portion 2. I eliminate the arrow or indicating mark from the rotatable timing ring and provide a removable pin 15 which answers as an indicating point upon the timing ring. Several apertures 16 may be formed in the timing ring, which apertures are made similar in appearance to the one which receives the pin 15, so that after the pin 15 is removed from the timing ring it will be impossible to determine which one of the apertures 16 was used as the indicating mark, thus defacing all indications from the fuse which

would show the position of the timing ring in relation to the graduated scale.

40

Having thus described my invention I claim and desire to secure by Letter Patent:

1. In a time fuse, an indicating member secured upon the fuse to facilitate in timing the fuse, and means for detachably securing the said member upon the fuse so that said member may be readily removed after the fuse is timed.

45

2. In a time fuse, a band having indicating means thereon to facilitate in timing the fuse and means for securing said band upon the fuse so that said band may be readily removed after the fuse is timed.

50

3. In a time fuse, a member having indicating means thereon to facilitate in timing the fuse, and fastening devices upon the ends of the said member for detachably securing the ends thereof together to form a band and for clamping said band upon the fuse so that said band may be readily removed after the fuse is timed.

55

4. In a time fuse comprising a fixed member and a rotatable timing member, the combination of a band having graduations thereon, said rotatable timing member having an indicating point thereon to be moved in relation to said graduations, means for securing said band upon the body portion of the fuse so that said band may be readily removed after the fuse is timed.

60

In testimony whereof I affix my signature in the presence of two witnesses.

DAVID A. GRANT.

Witnesses:

ROBERT M. WALLACE,

EARL D. SHAFFER.
